UNITED STATES PATENT OFFICE.

EARL O. CILLEY, OF CONKLIN, AND ITHIEL J. CILLEY, OF GRAND RAPIDS, MICHIGAN.

BURGLAR-GUARD.

1,191,400.

Specification of Letters Patent. Patented July 18, 1916.

Application filed April 13, 1914. Serial No. 631,670.

To all whom it may concern:

Be it known that we, EARL O. CILLEY and ITHIEL J. CILLEY, citizens of the United States, residing at Conklin and Grand Rapids, respectively, in the counties of Ottawa and Kent, respectively, and State of Michigan, have invented certain new and useful Improvements in Burglar-Guards, of which the following is a specification.

10 This invention relates to improvements in appliances for use in stores, banks, express cars and other places where valuables are kept, and especially in banks, jewelry stores, and the like, where daylight "hold ups" are likely to occur, for the purpose of preventing robberies, and its object is to so overcome the would be robber as to render it impossible for him to carry out his designs, or to escape with booty before he could be 15 disarmed and placed under arrest, and, at the same time, to place him in such a condition as to render it impossible for him to injure a teller, clerk or express agent by shooting him, or otherwise. This object is 20 attained by the mechanism and means indicated in the accompanying drawing in which—

Figure 1 is a perspective of a part of a counter with one end shown in section to 25 disclose the location and indicate the operation of this invention. Fig. 2 is a back elevation of a counter showing the practical distribution of several of the discharge, or spraying appliances forming a part of this 30 invention.

Similar letters refer to similar parts throughout the several views.

It is a well known fact that in case of "hold ups" in banks, stores, express offices or 35 cars, &c., the first act of the would be robber is to place the teller, clerk or agent in such a condition, as by sternly threatening him with a revolver or other destructive weapon that he cannot possibly defend himself or 40 the treasure he has in charge, and in many instances instant death is the penalty of but slight opposition. With this invention it is proposed to so locate and arrange spraying appliances, or other devices, that a very fine 45 and forcible spray of extremely pungent and volatile liquid may be thrown in such a manner as not to permanently injure "the hold up man," but to so quickly and thoroughly impregnate the air he must breathe as to 50 temporarily strangle and blind him and to

render him incapable of using his weapon effectively, or to successfully resist arrest or disarmature.

To bring about these results a very strongly charged compression tank, as 2, is placed in a convenient position in a store or bank, preferably under the counter 1, where it could not be readily seen or reached by the intruder, and a conductor pipe 3 is connected with this tank, extending therefrom to any 65 desired point in the building. From the conductor pipe 3 a series of discharge pipes 5 are extended through the front of the counter, or to any other desired location or position, so as to be made to discharge outside of the counter, as indicated in Fig. 2, 70 so that anyone standing outside of the counter would be in the direct range of the discharge. These discharge pipes are provided with cut off valves, as indicated at 75 7, which are located between the conductor pipe 3 and the necessary reservoirs 4 which are designed to hold the volatile liquid, hereinbefore described. The reservoirs 4 are so connected with the discharge pipes 5, by 80 means of curved pipes 6, as to form a very strong current to draw the liquid from the reservoirs 4 when the valves 7 are opened so that the pressure from the chamber 2 may escape through the discharge pipes 5. 85

The valves 7 may be actuated to open at the proper and desired times by any of the well known means for accomplishing the desired results. In Fig. 1 of the drawing we have shown an electrically operated trip for 90 the purpose. In this case we have shown the valve lever 16 supported by a link 10 which is suspended from a hook *c* on the lever 9, which lever is pivotally supported under the counter 1, as at *d*, and temporarily supported at the other end by a latch *e* on the slide 11 in such a manner that when the magnet 12 is energized from the battery 14, or by any other available means, the slide 11 will be drawn from under the lever 9 100 and the weight 8 will draw the lever 16 downward, as indicated by its dotted lines in Fig. 1, and open the valve 7 and allow of the free escape of pressure from the tank 2 through the respective pipe 5 and to the 105 open air, as at *b*, as indicated in said Fig. 7.

When operating the valve trips by electricity, as hereinbefore indicated, we propose to place the switches 13 at various points in the store or bank so that any em- 110

ployee may actuate the desired trip, and to so place the switches that the man threatened may slide his hand over his key when raising his hands, and open up his valve without any perceptible effort to do so. It is, of course, to be understood that these switches may be placed at any conveniently available point, as in the surface of the counter and set in so there will be no danger of accidentally operating them, in the edge of the counter, at a distant desk or other available place.

It will be readily understood that this appliance need not be confined to the use of a volatile liquid; as an easily diffused, pungent powder may be used with good success, but the liquid is preferable as it is not so likely to permanently injure the eyes or tender parts of the nostrils, as Cayenne pepper or strong snuff might do.

What we claim as new, and desire to secure by Letters Patent of the United States, is:

1. In combination with a counter having small openings at given points through the front, a strongly charged compression chamber back of the counter, a conductor pipe leading from the compression chamber, discharge pipes leading from the conductor pipe to the said small openings, tanks containing volatile liquid, pipes leading from the tanks into the discharge pipes, respectively, valves in the discharge pipes, and means for actuating said valves to open and

close the discharge pipes, as and for the purpose set forth.

2. In combination with a counter having openings through the front near the top at given points, a strongly charged compression chamber back of the counter, a conductor pipe leading from the compression chamber, tanks located back of the counter adjacent to the said openings, discharge pipes leading from the conductor pipe to said openings, valves in said discharge pipes, a pipe leading from each tank into its respective discharge pipe, and electromagnets and weights arranged to operate the valves as desired.

3. In combination with a counter structure having openings at given points, a strongly charged compression chamber back of the structure, a conductor pipe leading from the compression chamber, tanks located back of the structure, and containing volatile liquid, discharge pipes leading from the conductor pipe to the openings in the structure, pipes leading from the tanks into said discharge pipes, and means for holding the pressure in the compression chamber or discharging it through the pipes at pleasure.

Signed at Grand Rapids Michigan April 1914.

EARL O. CILLEY.

ITHIEL J. CILLEY.
